Primary Examiner — Kendra Leslie Hamilton**Assistant Examiner** — Amanda Christensen(74) **Attorney, Agent, or Firm** — Gerald Hespos; Michael Porco; Matthew Hespos(57) **CLAIM**

The ornamental design for a charging station, as shown and described.

DESCRIPTION

FIG. 1 is a top, front, right side perspective view of a charging station, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view thereof.

The broken lines depict portions of the charging station that form no part of the claimed design.
